UNITED STATES PATENT OFFICE.

HENRY ROSENTHAL, OF NEW YORK, N. Y.

BRUSH.

SPECIFICATION forming part of Letters Patent No. 349,407, dated September 21, 1886.

Application filed February 10, 1886. Serial No. 191,412. (No model.)

To all whom it may concern:

Be it known that I, HENRY ROSENTHAL, of the city, county, and State of New York, have invented certain new and useful Improvements 5 in Brushes, of which the following is a specification.

Heretofore flat brushes—such as whitewash or paste brushes—were made by placing the upper ends of the bristles around the lower 10 end of the handle, and then fastening them by bands passed around the upper ends of the bristles; or they were arranged by placing the upper ends of the bristles around a core, and cementing the upper ends of the bristles together 15 and passing a metal band around the same, as shown in the Patent No. 327,723, granted to me on October 6, 1885. I have found that in driving the nails through the leather and metal bands passed around the 20 upper ends of the bristles the cement used for holding the upper ends of the bristles together is cracked, and is pressed by the metal band against the bristles and cuts them, so as to cause them to be released from the handle.

25 The object of my invention is to construct the brushes in such manner that the cement is not chipped or broken by driving the nails through the bands and between the upper ends of the bristles, and consequently the cutting 30 of the bristles is prevented.

The invention consists in the combination of parts and details, as will be fully described hereinafter, and finally be pointed out in the claim.

35 In the accompanying drawings, Figure 1 is a side view of my improved brush, parts being broken out and others in section. Fig. 2 is a sectional view of the same on line $\alpha\alpha$, Fig. 1. Figs. 3, 4, 5, and 6 are detail side views of 40 the apertures or slotted cores or ferrules used in the brush.

Similar letters of reference indicate corresponding parts.

In making the brush the upper ends of the 45 bristles A are placed on the outside of an interior ferrule or hollow core, shaped the same as the lower end of the handle C, which is to be passed into it. The bristles, after having been placed around the ferrule B, are cemented together and surrounded by an exterior 50 metal ferrule, E, which is provided with lon-

itudinal or transverse slots, E', or may be provided with apertures, as shown in Fig. 5, or may be made of wire-netting, the size of the ferrule being such as to adapt it to receive the bristles and the core around which they have been placed. The lower end of the handle C is then inserted into the interior ferrule, and a strip, F, of leather, fabric, or other like flexible material is passed around the exterior 60 ferrule, the lower edge of said strip projecting slightly below the lower edge of the ferrule, and then tacks or nails G are driven through the slots of the ferrule, and through the bristles into the handle C, whereby the ferrules B 65 and E and the strip F are held securely on the handle, as are also the upper ends of the bristles A, which are cemented together. If the exterior ferrule, E, were not provided with slots or apertures, the awl forced through 70 said ferrule to make the holes for the nails or tacks would cause the metal to bulge on the inner side of the ferrule, and said bulged or raised parts of the ferrule would crack the cement and press the sharp edges of the cement 75 against the bristles and cut the same. By providing the slots in the ferrules the nails can be driven through the ferrule and the cement surrounding the bristles without in any way cutting or injuring the bristles. The 80 labor of punching the holes through the ferrules by means of an awl, after the ferrule has been placed around the handle, is also avoided, and thus the cost of manufacture reduced.

Having thus described my invention, I claim 85 as new and desire to secure by Letters Patent—

In a brush, the combination, with a handle, of an interior ferrule surrounding the handle, bristles surrounding the interior ferrule, a ferrule surrounding the bristles, and a strip or 90 band passed around the exterior ferrule, and of tacks or nails driven through the band, ferrule, bristles, and core into the handle, substantially as shown and described.

In testimony that I claim the foregoing as 95 my invention I have signed my name in presence of two subscribing witnesses.

HENRY ROSENTHAL.
